UNITED STATES PATENT OFFICE.

ADOLPH FRANK, OF NEW YORK, N. Y.

DESIGN FOR A STONE-SETTING.

59,552.

Specification for Design.

Patented Nov. 1, 1921.

Application filed April 9, 1921. Serial No. 460,074. Term of patent 7 years.

To all whom it may concern:

Be it known that I, ADOLPH FRANK, a citizen of Germany, residing at the city of New York, borough of Manhattan, in the county of New York and State of New York, have invented a new, original, and ornamental Design for Stone-Settings, of which the following is a specification.

Reference being had to the accompanying drawing, forming part thereof in which;

Figure 1 is a side view of the stone setting.

Fig. 2 is a top plan view thereof.

I claim:

The ornamental design for a stone setting, as shown.

ADOLPH FRANK.
